UNITED STATES PATENT OFFICE

CHARLES E. RORER AND ALBERT R. MITTERER, OF DENVER, COLORADO, ASSIGNORS
TO STADIUM STORES, INC., OF DENVER, COLORADO

STORE

Application filed August 28, 1928. Serial No. 302,494.

This invention relates to stores of the self-serve type and its principal object is to provide an arrangement of counters, checking stand, entrances, exits and other appliances and installations that permits of the display of merchandise to the best advantage and its ready inspection by customers passing through the store.

Another object of the invention resides in providing a store arrangement that permits of replenishing the merchandise by attendants without interfering with the customers, a further object is to provide means readily accessible to purchasers to ascertain the weight of goods taken from the display shelves, another object is to provide in a self-serving store, a simple and effective method for preserving perishable merchandise by refrigeration and moisture. A further object is to provide for the attractive display of merchandise in a sale-room in such a manner that all the merchandise can be seen from any point in the room, both by the customers and by the checking clerks, and still other objects reside in details of construction and in other novel arrangements and combinations of parts as will be brought out in the course of the following description.

In the accompanying drawings in the several views, of which like parts are similarly designated,

Figure 1 represents a plan view of the improved store-arrangement,

Figure 2, a section taken on the line 2—2,
Figure 1,

Figure 3, a section along the line 3—3,
Figure 1, and

Figure 4, a perspective view of one of the weighing appliances included in the arrangement.

In Figure 1 of the drawings the reference numeral 5 designates a store room having a front-wall 6, with display-windows 7 and an entrance-door 8.

The rear wall of the store has not been shown for lack of space, but it is to be understood that the rear wall may as usual, have one or more doors through which merchandise can be supplied to a storage space 14 in the back of the room.

The outstanding feature of the installation is a display stand 9 of U-shaped or horse-shoe form, the sides 10 of which may extend parallel to the side walls 12 of the store room and the curve 13 of which faces the front wall 55 of the same.

The stand is made of upright walls and a top to provide a case 15 useful mainly for the storage of merchandise and for the installation of pipes 16 of a refrigeration system by which perishable merchandise is kept from spoiling.

The walls of the case may be made of insulating material and the case has a plurality of doors 17 in its outer wall to afford access to the contents of the case.

The front wall of the case may also be provided with doors as at 18, and the case may have shelves 19 accessible to the customers, behind one or more of these doors, for the storage of merchandise requiring constant refrigeration such as butter, milk, eggs, etc.

The top 20 of the stand slants from its rear wall forwardly and it may be divided into a number of stalls by a front wall 21, a rear wall 22 and transverse partitions 23. In order to vary the size of these stalls, the partitions may be adjustable, and a convenient method of adjusting the partitions consists in providing the rear and front walls 75 of the stalls with upright slots 24, best shown in Figure 4, and by forming the partitions at their ends with tongues 25 that loosely fit into the slots.

In front of the slanting stalls at the lower ends thereof is a weighing shelf 26 equipped with movable platforms 27, dials 28 to indicate the weight of articles supported on the platforms, and parallel rails 29 to facilitate the sliding movement of baskets with merchandise to and from the platforms. The shelf may be supported on brackets 30 forward of the front wall of the case, as shown in Figure 2, or it may form the top of the portion or portions of the case containing shelves 19, as illustrated in Figure 3.

The slanting top of the casing may be directly exposed to the refrigerant effect of a cooling fluid in the pipes of the case, as is necessary for the preservation of highly 100

perishable products such as vegetables, or a false top 31 may be interposed between the slanting top and the interior of the case containing the refrigeration pipes, as has 5 been illustrated in Figure 3. The last mentioned arrangement is of particular value for stalls used for the storage and display of fruits.

10 Removable covers 32, may be provided to protect the contents of part or all of the stalls and a spray-pipe 33 may be installed above the vegetable stalls to supply water to the green garden produce and thereby keep it in fresh condition.

15 The U-shaped display stand is arranged with relation to the walls of the store room to provide a vestibule 34 in the front portion thereof, the before mentioned storage room 14 in the back portion of the same 20 and a corridor 35 around the entire stand. A high screen 36 separates the portion of the corridor at the curve of the stand from the storage room.

25 The corridor is closed at the front of the stand by doors or gates 37 which prevent customers and other unauthorized persons from entering the same, it being a feature of the invention that the spaces outside the U-shaped stand, are provided for the convenience of employees of the establishment, only.

30 The space 38 within the horseshoe is closed at the front thereof by a railing 39 having an entrance 40 and an exit 41 at opposite sides of a cross-railing 42 that extends a short 35 distance into the space inside the U-shaped stand. The entrance and the exit may have gates of the turn-style kind if so desired.

35 The cross-rail 42 divides the front of the space inside the stand into a passage 43 leading to the greater portion of the space and an office 44 containing a desk 45 for the checkers or cashiers of the store.

40 In the passage 43 is a rack 46 for the support of baskets used by the customers to carry 45 their purchases to the desk.

45 In the vestibule are benches 47 for window-displays and a partition 48 to provide a direct passage for customers to the front door after they have passed around the checking desk.

50 Persons entering the sale room within the horse-shoe, obtain a view of all the merchandise on display. Their selection of purchases is thus greatly facilitated and they may go directly to the stalls containing the desired 55 goods, and thereby avoid the annoyance experienced on other stores of similar character in which customers are compelled to follow a circuitous route or path in order to obtain any of the merchandise that is for sale.

60 The selected merchandise is placed in the baskets taken from the rack 46 in the passage and it may be weighed by placing it on any one of the platforms of the weighing devices installed at the front of the stand. The movement of the baskets to and from the scales is

greatly facilitated by the rails along which they can be slid with very little effort.

65 After the customer has selected the goods to be purchased, he or she passes around the checkers desk, where the purchased articles 70 are packed and paid for. The customer then leaves the sales room through the exit and passes from the store through the front door.

The employees of the store entrusted with 75 the sale of the merchandise, are in the corridor outside of the U-shaped stand where they have access to all of the stalls on top of the stand and to the inside of the case in the body portion of the stand at any point thereof. The attendants thus may replenish stands 80 with fresh goods as fast as they are emptied or partially emptied by the customers, and the goods are readily obtained from the supplies stored in the storage room back of the stand.

85 It is an outstanding feature of the arrangement that the customers and the attendants never interfere with each other and that the attendants are in a position to assist the customers at any point of the stand or counter. 90

95 The slanting top of the stand functions to display the goods to the best advantage, it gives the appearance of larger quantities than are really contained in the stalls and it causes the goods to move downwardly with in easy reach of the customers, as fast as parts of the goods are removed.

100 The refrigeration system and the water spray keep the goods on and in the stand in fresh condition and the entire business may be transacted in one room without the use of a basement or other separate storage space. Sacks and bags for the merchandise may be suspended for easy access beneath the weighing shelf.

105 Racks 49 may be placed on the slanting top to support the goods in spaced relation thereto.

110 What we claim and desire to secure by Letters Patent is:

1. In a store of the character described, a U-shaped display stand dividing a floor space of the store into a space for customers on the inside of the stand and a corridor for employees on the outside of the same, the stand having a top for the support of merchandise, sloping upwardly from the customers space to the corridor.

115 2. In a store, a U-shaped display stand providing a space for customers having an entrance at an end of the store, and a screen spaced from the stand at the opposite end of the store, the screen and the side-walls of the store forming a corridor around the stand, and the screen defining a storage space screened from the space for customers.

120 3. In a store, a U-shaped display stand providing a space for customers having an entrance at an end of the store, and a screen spaced from the stand at the opposite end of the

the store, the screen defining a storage space at the said opposite end of the store and adapted to hide the storage space from the space for customers.

divide the surface into stalls of variable widths, a space for merchandise within said stand, and means affording access to the interior of the stand from both sides thereof.

5 4. In a store, a U-shaped display stand providing a space for customers interiorly of the stand and a space for employees outside the same, the top surface of the stand sloping from the space for customers upwardly to
10 the space for employees, a space for merchandise within said stand, and means affording access to the interior of the stand from both sides thereof.

10. In a store, a U-shaped display stand dividing floor space of the store into a space within the stand for customers, and a space outside the stand for employees, the stand having a stationary top for the display of merchandise, sloping upwardly from the customers' space to the employees' space. 75

15 5. In a store, a U-shaped display stand providing a space for customers interiorly of the stand and a space for employees outside the same, the top surface of the stand sloping from the space for customers upwardly, and transverse partitions dividing said surface into stalls, a space for merchandise within said stand, and means affording access to the interior of the stand from both sides thereof.

11. In a store, a **U**-shaped display stand dividing floor space of the store into separate spaces for customers and for employees, the stand having a top for the display of merchandise, sloping upwardly from the customer's space to the employees' space.

25   6. In a store, a U-shaped display stand providing a space for customers interiorly of the stand and a space for employees outside the same, the top surface of the stand sloping from the space for customers upwardly, and transverse partitions dividing said surface into stalls, the partitions being separately 30 movable to vary the width of the stalls, a space for merchandise within said stand, and means affording access to the interior of the stand from both sides thereof.

In testimony whereof we have affixed our signatures.

CHARLES E. RORER.
ALBERT R. MITTERER

35 7. In a store, a U-shaped display stand providing a space for customers interiorly of the stand and a space for employees outside the same, the top surface of the stand sloping from the space for customers upwardly, and
40 a wall at the upper edge of the surface to retain merchandise upon the same, a space for merchandise within said stand, and means affording access to the interior of the stand from both sides thereof.

45 8. In a store, a U-shaped display stand providing a space for customers interiorly of the stand and a space for employees outside the same, the top surface of the stand sloping from the space for customers upwardly, a
50 wall at the upper edge of the surface to retain merchandise upon the same, and transverse partitions cooperating with the wall to divide the surface into stalls, a space for merchandise within said stand, and means
55 affording access to the interior of the stand from both sides thereof.

9. In a store, a U-shaped display stand providing a space for customers interiorly of the stand and a space for employees outside the same, the top surface of the stand sloping from the space for customers upwardly, a wall at the upper edge of the surface to retain merchandise upon the same, and transverse partitions connected with the wall for adjustment to selective positions, whereby to
